CONVERTIBLE PLAY PEN AND CRIB

Eric R. Bourdon, Biloxi, Miss.

Application April 22, 1947, Serial No. 743,058

4 Claims. (Cl. 5—93)

1

This invention relates to children's furniture and more particularly to a combined and convertible crib and play pen.

An object of the present invention is to provide an improved and simplified structure readily convertible without tools into either a crib or play pen.

A further object of the invention is to provide an article of the type indicated which will conform generally to the conventional appearance of either a crib or play pen and which will embody all of the advantages as to adjustability and the like of a conventional crib when contracted to the crib size.

Further objects will more particularly appear in the course of the following detailed description.

The invention consists in the novel construction, arrangement and combinations of parts hereinafter more particularly described and claimed.

Two sheets of drawings accompany this specification as part thereof, in which like reference characters indicate like parts throughout.

In the drawings:

Figure 1 is a perspective view of an embodiment of the present invention showing the device contracted to crib form;

Figure 2 is a perspective view of the present invention showing the initial stage of expanding the crib into a play pen;

Figure 3 is a perspective view of the improved device expanded into the play pen form;

Figure 4 is a fragmentary detail of one corner of the expandable side panel structure;

Figure 5 is a fragmentary cross section taken on line 5—5 of Figure 4;

Figure 6 is a fragmentary plan view of the right hand front corner of Figure 1;

Figure 7 is a fragmentary cross section taken on line 7—7 of Figure 1, and

Figure 8 is a fragmentary cross section taken on line 8—8 of Figure 3.

The drawings illustrate one embodiment of the present invention and show conventional head and foot board panels 1, each associated with conventional bed posts 3, the two head and foot panels 1—1 being rigidly associated by a side panel 2 herein illustrated as comprising rail members 4 spaced by a plurality of slats 5.

The inner faces of the corner posts 3 are provided with spaced hook members 10 by means of which the bottom 7 can be supported at adjustable heights as by hangers 11.

The bottom comprises two similar planar panels 6 and 7 which are hingedly associated as by hinges

2

8 at the adjacent edges of these panels so that panel 6 can be selectively folded back into superposed position on panel 7, as shown in Figure 7, or can be folded out into a common plane with panel 7, as illustrated in Figure 8.

To the upper face of the upper bottom panel 6 when the latter is superposed over the bottom panel 7, is fixedly secured conventional spring structure S and mattress structure M, so that when the upper bottom panel 6 is superposed over bottom panel 7, the mattress M is on the upper face of the bottom in its conventional position for use in the crib. On the other hand, when the bottom panel 6 is folded outwardly as illustrated in Figure 8 into a common plane with the bottom panel 7, the spring and mattress structure depend below the bottom panel 6.

An expandable front panel is provided for the frame of the bed comprising a plurality of similar panels 14 associated by their adjacent vertical edges by means of hinges 15. The outermost panels 14—14 are hingedly mounted upon suspension rods 12—12 carried by the front bed posts 3—3, and are both rotatable and slidable on these rods 12 so that the height of the expandable panel as an entirety can be readily adjusted.

Conventional latches 17 are provided so that the sections 14 of the expandable front panel can be secured both in their folded position as illustrated in Figure 1, and in their expanded position as illustrated in Figure 3.

For securing the expandable front panel in various positions the rods 12 may conveniently be provided with spaced notches 13, as illustrated in Figure 4, and latch members 20 will be secured against the rear faces of the end sections 14, these latch members 20 being normally biased into latching position as by springs 21 and manipulated by handles 22. Any convenient latch means can be substituted and various other variations in the precise structure will readily suggest themselves to those skilled in the art, both with respect to the artistic design and details of arrangement, but within the scope of the present invention as claimed.

Having thus fully described my invention, what I claim is:

1. Convertible crib and play pen comprising head and foot boards, a side panel rigidly associating said head and foot boards, a bottom comprising two flat panels hingedly connected by adjacent edges, spring and mattress structure mounted on the upper face of the upper of said bottom panels, a second side panel comprising a plurality of sections hingedly associated by their

adjacent vertical edges, said sections proportioned to constitute a side panel for the crib when folded into overlaid position and to constitute a side panel and supplemental foot and head boards when extended to conform with the top panel of the bottom when the latter is unfolded to bring the spring and mattress structure on its under side, and means hingedly associating the end sections of said second panel with the head and foot boards respectively.

2. Convertible crib and play pen comprising head and foot boards, a side panel associating said head and foot boards, a bottom comprising two flat panels the size of the crib said panels hingedly connected by adjacent edges, spring and mattress structure mounted on the upper face of the top panel when the latter is folded over the bottom panel, an expansible side panel comprising a plurality of sections hingedly associated by adjacent vertical edges, the end sections of said expansible panel mounted by their outer vertical edges to hinge and slide vertically with respect to the head and foot boards, means for removably securing the sections of the expansible side panel selectively in open and folded relationship and means for supporting the bottom at selected heights with respect to the head and foot boards.

3. Convertible crib and play pen comprising a frame including parallel spaced end panels and a connecting side panel, a removable bottom, means for vertically adjusting the bottom with respect to the frame, the bottom comprising two flat panels hingedly associated by adjacent edges, spring and mattress mounted on the upper face of the upper bottom panel when the latter is superposed on the other bottom panel, an expansible side panel comprising a plurality of sections

hingedly connected by adjacent vertical edges, means for pivotally and slidably associating the end sections of said expansible side panel with the end panels, and means for securing said hinged sections in both folded and expanded positions.

4. Convertible crib and play pen comprising a bottom formed of two planar panels associated by hinges on adjacent edges to permit folding one over the other or into a common plane as desired, 10 spring and mattress structure secured to the upper face of one panel when said panels are in superposed position, fixedly associated frame post members, side and end panels, spaced and 15 arranged to support said superposed bottom panels, supplementary side panels and means for adjustably associating said supplementary panels with respect to each other and the frame posts to conform with the perimeter of the bottom in 20 both folded and unfolded position.
